Primary Examiner — Jennifer L. Watkins

Assistant Examiner — Samantha Lynne Brodowski

(57) **CLAIM**

The ornamental design for a wallet, as shown and described.

DESCRIPTION

FIG. 1 is a top perspective view of a wallet showing our new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right elevation view thereof;

FIG. 8 is a left elevation view thereof;

FIG. 9 is another reduced top perspective view thereof, with the wallet shown in an open position;

FIG. 10 is a reduced perspective view of the wallet in FIG. 1, shown in an unfolded, flat position;

FIG. 11 is a front elevation view thereof;

FIG. 12 is a rear elevation view thereof;

FIG. 13 is a top plan view thereof;

FIG. 14 is a bottom plan view thereof;

FIG. 15 is a right elevation view thereof; and,

FIG. 16 is a left elevation view thereof.

The broken lines on claimed surfaces in FIGS. 10-12 depict fold lines that are environmental structure and form no part of the claim. The broken lines in FIGS. 10-12 adjacent to and around unshaded surfaces depict adhesive portions that are environmental structure and form no part of the claim. The broken lines in FIGS. 10-16 depict truncated triangular tabs that are environmental structure and form no part of the claim.

1 Claim, 16 Drawing Sheets
